GERMICIDE

William Nelson Axe and Douglas D. Henson,
Austin, Tex., assignors to Union Oil Company
of California, Los Angeles, Calif., a corporation
of California

No Drawing. Application July 20, 1937,
Serial No. 154,626

4 Claims. (Cl. 167—22)

This invention relates to a germicide or bactericide and the method of producing the same. More specifically the invention relates to a germicide or bactericide from nitrogen bases recovered from certain petroleum fractions.

It has been discovered that nitrogen bases recovered from certain petroleum fractions possess germicidal properties which render them especially valuable as bactericides. These nitrogen bases exist in many crude oils and are found in appreciable quantities in asphalt base oil, such as California petroleum.

The invention, therefore, resides in recovering the nitrogen bases from petroleum and producing a bactericide from said bases. In producing the bactericide or germicide the bases are converted to a water soluble form by conversion to a readily water soluble salt. Treatment of the bases with a mineral acid, such as dilute hydrochloric acid produces a salt which is highly water soluble. Other mineral acids, such as hydrobromic, hydro-iodic, sulphurous, phosphoric, or sulphuric acid may be employed to convert these bases into a water soluble form. However, I prefer to use dilute hydrochloric acid. These bases dissolved in dilute hydrochloric acid exhibit appreciable bactericidal action. However, I find that if these bases are precipitated from solution in a high state of dispersion then bactericidal efficiency is materially increased.

It is, therefore, an object of the present invention to recover nitrogen bases from petroleum, or other allied sources, such as coal tar, and then produce a germicide or bactericide from said bases by forming a dispersion of said bases.

It is another object of this invention to convert nitrogen bases into water soluble salts, dissolve said salts in water and then form a germicide from said solution by precipitating the bases from said solution in a fine state of dispersion.

It is another object of the invention to produce a germicide by converting nitrogen bases into a water soluble form by treatment with a mineral acid, such as dilute hydrochloric acid, dissolving the acid treated bases in water and precipitating the bases therefrom by the addition of a buffer agent. As buffer agents I may use soluble peptones or other natural or prepared buffer agents. Sodium acetate-hydrochloric acid buffers of pH between 3.0 to 4.5 will precipitate the bases. Since peptone and horse serum are capable of bringing about precipitation it is believed that any soluble protein will accomplish the same result. Natural buffers are preferred in the preparation of germicides because of their non-toxic nature. The most available protein for this purpose is gelatin.

Other objects will appear from the following description:

60 Bases from petroleum distillates are of unusual

pharmacological interest because, unlike volatile bases from other natural sources, they contain in decidedly preponderant amount non-aromatic types of unknown structure. For many of these products a cyclopentane, or so-called naphthenic structure, is highly probable. Were these products of plant occurrence, they would be classed as alkaloids; however, they differ from the most important plant alkaloids in being volatile and oxygen free.

During the exhaustive investigation of petroleum bases their apparent low toxicity has suggested the possible discovery of products of therapeutic value; so, to determine the particular fractions and types of these bases of greatest promise for a pharmacological study, a determination of their germicidal action appeared desirable. Since experiment has indicated that the higher boiling bases containing the most potent bactericidal material, a study of transformer-oil bases was inaugurated. After a preliminary examination of the bactericidal action of various base fractions, the following determinations were made on a promising aromatic and likewise on a non-aromatic portion having approximate average boiling points of 340° C.: (1) accurate phenol coefficients at 20° and 37° C. against strains of *Eberthella typhi* and *Staphylococcus aureus*; (2) the effect of horse serum on their germicidal action; (3) mycostatic action against the above mentioned bacterial; (4) the effect of a small amount of the bases on agar plates heavily seeded with bacterial; (5) the action of the total acidity of the hydrochloride solutions on bacteria.

In refining California asphalt base petroleum transformer-oil stock with liquid sulphur dioxide, this solvent withdraws the small amount of contained nitrogen bases and, after its recovery, the residual volume of hydrocarbon oil constitutes what is known as an Edeleanu extract. Five hundred barrels of this extract was processed as follows: The bases were extracted with 15% sulphuric acid, then liberated with sodium hydroxide and finally divided into three fractions (I, II, III) by vacuum distillation from a laboratory shell still. The yield of bases was 3 3/4 barrels.

TABLE I.—Physical constants of transformer-oil bases

Fraction	N 25/D	D 15.5°/4
I.....	1.5431	0.984
II.....	1.5595	1.005
III.....	1.5864	1.039

Stock laboratory cultures of *E. typhi* (Rawlings strain) and *Staph. aureus* (a laboratory strain) were used in all tests. Although the Rawlings strain is not the standard recommended in the

F. D. A. method for the determination of phenol coefficients, the remarkable constancy, observed by other investigators and verified in this work, justifies its use. The resistance of the *E. typhi* culture employed fell within the prescribed limits in every instance over a period of six months. The minimal resistance usually prescribed for *Staph. aureus* is survival of the bacterial for five minutes in a 1:60 dilution of phenol, whereas 10 the particular culture used in these tests showed a slightly weaker but constant resistance. Growth after contact for five minutes in a 1:70 dilution of phenol was observed in each control run. At 37° C. a resistance similar to the conditions stated above appeared with phenol dilutions of 1:100, whereas the F. D. A. standard resistance limit should be found with a dilution of 1:80.

Since transformer-oil bases are insoluble in water, a readily soluble salt was selected for this work. Solutions of these bases in dilute hydrochloric acid exhibited considerable bactericidal efficiency. However, under the experimental conditions employed the peptone in the culture medium, by virtue of its buffer action, precipitates the petroleum bases in a high state of dispersion; accordingly, it should be emphasized that our measurements apply to free bases liberated in situ as a fine emulsion.

30 The stock solutions of the bases were made up with standard N/10 acid, hence the acidity of any particular dilution was known quite accurately. Although the wide variation in phenol coefficients of a series of fractions having the same acid content apparently precluded the possibility of the acid being the active germicidal agent, this conclusion was confirmed by control tests with the bases omitted.

Fraction I (Table I) in 6 N hydrochloric acid 40 was extracted with chloroform. In this way, the aromatic hydrochlorides were segregated in the aqueous layer and the non-aromatic hydrochlorides in the chloroform layer. The liberated aromatic bases (6.5% of the total) had an N 25/D value of 1.6020 and for the non-aromatics this value was 1.5364.

The aromatic bases were separated into 27 fractions by distillation through a reflux column under diminished pressure. Stock solutions of 50 (1) the crude bases, (2) the unfractionated non-aromatics and (3) aromatic fractions 2 and 27, were prepared by dissolving 1 g. samples in just the requisite amount of N/10 hydrochloric acid. The results obtained from these preparations are 55 compiled in Table II.

TABLE II.—*Phenol coefficients of transformer-oil bases*

60	Fraction	B. p.	N 25/D	Phenol coefficient (F. D. A.)
I (crude bases)			1.5431	5.0
INA (crude non-aromatic)			1.5364	2.0
IA ₂₇ (aromatic)	276-279° C.		1.5614	2.0
IA ₂₈ (aromatic)	340° (dec.)		1.6604	7.0

In order to determine if any exaltation in germicidal power occurs in the higher boiling bases, 70 the original fractions II and III (Table I) were distilled under reduced pressure from a Claisen flask, the distillate from each sample being collected in two equal portions. Stock hydrochloride solutions were prepared as before and used in arriving at the following phenol coefficients:

TABLE III.—*Phenol coefficients of mixed type bases*

Fraction	Phenol coefficient (F. D. A.)	5
II		6.4
II ₁		8.0
II ₂		9.0
II ₃		10.6
		10

The phenol coefficients of the preceding roughly fractionated bases indicated that a more thorough examination of Fraction III would be profitable. Consequently a portion of bases from this latter source were extracted with chloroform under conditions the same as those observed in processing Fraction I. The regained aromatics representing 12% of the total were resolved into five fractions by distillation at 12 mm. pressure from a Claisen flask and the usual hydrochloride solutions prepared.

TABLE IV.—*Distillation data of aromatic transformer-oil bases*

Fraction	Distilling temp. at 23 mm.	N 25/D	25
III _{A1}	° C. 232-236	1.6470	30
III _{A2}	236-238	1.6600	
III _{A3}	238-240	1.6620	
III _{A4}	240-247	1.6630	
III _{A5}	247-265	1.6666	

Since dilutions of these fractions showed no exaltation in germicidal power over the more well defined aromatic cuts of Fraction I, their exact coefficients were not determined.

From 100 cc. of regained non-aromatic bases (III) distilled under 23 mm. pressure, 80 cc. was collected in 10 cc. portions and the phenol coefficients of fractions 1, 4, 5, 6 and 8 in dilute hydrochloric acid were determined.

TABLE V.—*Distillation data and phenol coefficients of non-aromatic transformer-oil bases*

Fraction	Distilling temp. at 23 mm.	N 25/D	Phenol coefficient (F. D. A.)	45
III _{NA1}	° C. 210-220	1.5564		50
III _{NA2}	220-224	1.5622		
III _{NA3}	224-227	1.5662		
III _{NA4}	227-232	1.5682		
III _{NA5}	232-237	1.5749		55
III _{NA6}	237-240	1.5786		
III _{NA7}	240-249	1.5825		
III _{NA8}	240-270	1.5910		

The phenol coefficients in Table V suggest that certain individual non-aromatic components in the higher boiling ranges possess exceptional 60 germicidal properties. However, it is worthy of note that fraction 5 has the maximum coefficient while the first and last cuts show identical values.

Phenol coefficients of fractions IA₂₇ (Table II) and III_{NA5} (Table V)

Stock 1:100 dilutions were made as follows: one gram of bases was dissolved by the drop-wise addition of standard N/10 hydrochloric acid. 70 The acid required for IA₂₇ and III_{NA5} solutions was 62.46 cc. and 65.82 cc., respectively. After removal of tarry matter and hydrocarbon oil, the solutions were diluted to 100 cc. with sterile distilled water. Although this procedure does not 75

- reveal the exact amount of bases in solution, reproducible results were possible. Furthermore, since all of the subsequent data are based on the original one gram of material, the inherent error 5 favors the resistant action of the bacteria rather than the germicidal effect of the bases. The pH values of the stock solutions, as estimated colorimetrically, were 3.8 and 4 for I_{A27} and III_{NA5} , respectively.
- 10 Phenol coefficients of the two fractions under consideration were redetermined with care using *E. typhi* as the test organism at 20° C., and were found to check the values previously listed. In these tests dilutions were prepared in volumetric 15 flasks rather than in the medication tubes.

*Growth observed in I_{A27} tubes containing 1:25 dilution of the base.

- 30 The mycostatic tests described herein were carried out according to standard procedure. Preliminary tests were made using the free I_{27} and III_{NA5} emulsified in agar medium. The tubes, cooled in slants, were streaked with a 4 mm. loop 35 holding a broth culture. Under these conditions growth of *E. typhi* and *Staph. aureus* was not inhibited.

The inhibiting action of base emulsions formed in situ from the hydrochloride solutions was also 40 studied. One cubic centimeter of various dilutions was added to sterile test-tubes with subsequent addition of 5 cc. of beef extract agar. The content of the tubes was thoroughly mixed and then allowed to harden in slants. Phenol dilutions were made up in an analogous manner, thus affording a basis of comparison. Blank tubes containing only agar medium served as controls. The slants were streaked with a 4 mm. loop as uniformly as possible. The results in Table VIII 50 refer to a 48 hour incubation period.

Tests on heavily seeded agar plates

Here the usual beef extract peptone agar was employed. Each plate contained 0.2 cc. of a 24 hour broth culture and 15 cc. of the agar medium. The base dilutions were applied by means of a single streak of a 2 mm. loop and the readings taken after a 48 hour incubation period. The plate containing *E. typhi* streaked with I_{A27} showed only a faint clear zone and the *Staph. aureus* plate streaked with the same dilution remained unchanged; in contrast, the 1:100 dilution of III_{NA5} gave well defined clear zones in both the *E. typhi* and *Staph. aureus* plates. Phenol dilutions of 1:90, 1:100 and 1:1000 were applied in like manner without any observable effect on the bacterial growth. In an additional test with *Staph. aureus* the germicides were applied to the heavily seeded plates through a saturated circular filter paper 6 mm. in diameter. Again I_{A27} was without effect in dilution of 1:100. However, III_{NA5} showed a clear zone in 1:100 and a faint clear zone at 1:1400 dilution.

Nitrogen bases compare very favorably with phenol as a bactericide. A resume of the inhibition experiments brings out the fact that growth of *E. typhi* of standard virulence is completely inhibited by sample I_{A27} and sample III_{NA5} in dilutions of 1:600, as compared with 1:480 for phenol. Although sample I_{A27} was ineffective ²⁰ *Staph. aureus* in the usual germicide tests, it inhibits the growth of the organism in dilution of 1:600. Likewise, III_{NA5} is highly efficient in this respect, inhibiting completely the growth of *Staph. aureus* in a dilution of 1:8400.

Experiments with ordinary emulsions of the free bases showed no appreciable germicidal action. Also it may be pointed out that emulsions of free bases in agar medium possess no inhibiting action against the bacteria used. However, in all of the phenol coefficient determinations a very pronounced turbidity, due to liberation of free bases, takes place upon addition of the broth culture. The buffer action of the peptone evidently takes up the hydrochloric acid, liberating the bases in a finely dispersed state. With respect to the inhibition tests, a similar action occurs with the broth-agar medium. The molten agar becomes perfectly opaque due to the liberated bases, yet inhibitory action is quite pronounced. Thus it would seem that an extremely fine emulsion is germicidal; whereas the macro droplets produced by agitating the bases with soap solution are without effect.

We claim:

1. In a process for the production of a germicide from water-soluble nitrogen base salt solutions obtained by treating nitrogen bases with a mineral acid and dissolving the soluble salts thus produced in water, the step of adding a buffer agent to said aqueous solution to precipitate the bases from solution in a fine state of dispersion.

2. A process according to claim 1 in which the nitrogen base is precipitated from the aqueous solution by means of a buffer agent having a pH range between 3.0 and 4.5.

3. A process according to claim 1 in which a soluble peptone is added to the aqueous solution of the nitrogen base salt to precipitate the nitrogen base therefrom.

4. A process according to claim 1 in which gelatin is added to the aqueous solution of the nitrogen base salt to precipitate the nitrogen base therefrom.
